UNITED STATES PATENT OFFICE.

PAUL TUSZKA, OF STEVENS POINT, WISCONSIN.

FOLDING CRANK-HANDLE.

1,191,855.

Specification of Letters Patent. Patented July 18, 1916.

Application filed May 11, 1916. Serial No. 96,928.

To all whom it may concern:

Be it known that I, PAUL TUSZKA, a citizen of the United States, residing at Stevens Point, in the county of Portage and State of Wisconsin, have invented certain new and useful Improvements in Folding Crank-Handles; and I do declare the following to be a full, clear, and exact description of the invention, such as will enable others skilled in the art to which it appertains to make and use the same.

My invention relates to improvements in crank handles and has for its object to provide a simply constructed and inexpensive device of this class which may be quickly and easily folded when not in use and extended when necessary, the improved handle being adapted for application to any machine where found desirable but being of unusual advantage for use on tools which must be carried from place to place and upon hand driven cream separators employed in cramped quarters.

With the foregoing general object in view, the invention resides in certain novel features of construction to be hereinafter fully described and claimed, the descriptive matter being supplemented by the accompanying drawing which constitutes a part of this application and in which:

Figure 1 is a side elevation of the improved crank handle showing several positions of the hand hold in dotted lines; Fig. 2 is an elevation at right angles to Fig. 1; Fig. 3 is a vertical section showing the hand hold in operative position; and Fig. 4 is a similar view showing the hand hold in readiness for swinging to another position.

In specifically describing the construction shown in the drawings above briefly described, similar characters will be placed on corresponding parts throughout the several views and reference will be herein made to the numerous elements by their respective indices. To this end, the numeral 1 designates the arm of the improved crank handle while 2 refers to the hand hold thereof. The arm 1 may be provided at one end with any preferred means for attaching it to a shaft or the like (not shown), said end being shown as having an opening 3 for this purpose. The other end of the arm 1 is notched at 4 to provide a pair of parallel ears 5, the inner end 6 of the notch constituting a stop shoulder for a purpose to be described.

The hand hold 2 is provided with a flat

head 8 at one end, said head being received between the ears 5 and having a longitudinally extending slot 9 through which a pivot screw or the like 10 passes, said screw being shown as extending through an aperture in one ear 5 and as being threaded in the other ear. A pin 11 extends from the inner end of the head 8 and is provided at its free end with a stop 12, a sleeve 13 being revolvably mounted on said pin between said stop and head.

The opposite edges 14 of the head 8 are disposed in parallel relation with the slot 9 while the outer end 15 of said head is formed on an arc whose center is disposed at the outer end of said slot. By this arrangement, when the hand hold 2 is moved to the position shown in Fig. 4 it may be swung to any one of the dotted line positions depicted in Fig. 1. When, however, said hand hold has been positioned in right angular relation with the arm 1 and is then forced toward said arm, one or the other of the edges 14 will abut the shoulder 6, whereby turning of the head 8 around the pivot pin 10 is prevented. Thus, the hand hold may be effectively locked in operative position or in a reverse position.

For the purpose of yieldably retaining the hand hold 2 in its numerous adjusted positions, a spring pressed-detent in the form of a pin 16 is slidably mounted in a bore 17 formed in the arm 1 and opening through the shoulder 6, said pin being moved into engagement with the head 8 by a coiled spring 18 housed in the bore 17 behind said pin. The outer end of pin 16 is rounded for yielding engagement with sockets 19 formed in the edges 14 and in the end 15 of the head 8.

By constructing the improved device in the manner shown and described, it will be obvious that regardless of the fact that it is extremely simple and inexpensive, it will be highly efficient and will operate to great advantage in numerous connections.

I claim:

1. A crank handle comprising an arm having an ear projecting longitudinally from one of its ends and having a shoulder at the inner end of said ear, a pivot projecting laterally from the ear in spaced relation to said shoulder, and a hand hold provided with a head contacting with said ear, said head having a slot extending longitudinally of the hand hold and having a

- straight edge parallel with said slot, said slot receiving the aforesaid pivot and said edge being adapted to abut said shoulder when the hand hold is swung into angular relation with the arm and then forced longitudinally toward said arm, the slot being of a length to permit said edge to clear said shoulder when the handle is shifted in the opposite direction, whereupon it may be 10 swung to another position.
2. A crank handle comprising an arm having an ear projecting longitudinally from one of its ends and having a shoulder at the inner end of said ear, a pivot projecting laterally from the ear in spaced relation to said shoulder, and a hand hold provided with a head contacting with said ear, said head having a slot extending longitudinally of the hand hold and having a straight edge 15 parallel with said slot, the outer end of said head being formed on an arc having its center disposed at the outer end of the slot, said slot receiving therein the pivot pin and said edge being adapted to abut said shoulder 20 when the hand hold is swung into angular relation with the arm and then forced longitudinally toward said arm, said edge and said end of the head having sockets formed therein, and a spring pressed detent for en- 25
- gagement with said sockets to yieldably retain the hand hold in its adjusted positions.
3. A joint of the class described comprising a member having an ear and a shoulder at the inner end of said ear, a pivot projecting laterally from the ear in spaced relation to said shoulder, a second member provided with a head contacting with said ear, said head having a slot extending longitudinally of said second member and having a straight edge parallel with said slot, said slot receiving the aforesaid pivot and said edge being adapted to abut said shoulder when the second member is swung into angular relation with the first named member and then forced toward the same, said slot being of a length to permit said edge to clear said shoulder when said second member is shifted in the opposite direction, whereupon it may be swung to another position.

In testimony whereof I have hereunto set my hand in presence of two subscribing witnesses.

PAUL TUSZKA.
